UNITED STATES PATENT OFFICE.

THOMAS FRANK, OF ST. LOUIS, MISSOURI.

HOSE MOP.

Application filed October 24, 1924. Serial No. 745,650.

To all whom it may concern:

Be it known that I, THOMAS FRANK, a citizen of the United States, residing at St. Louis, Missouri, have invented a certain 5 new and useful Improvement in Hose Mops, of which the following is a specification, such as will enable others skilled in the art to which it appertains to make and use the same.

10 My invention relates to devices adapted to be attached to the end of a hose for the purpose of washing windows, automobiles or other articles.

The objects of my invention are to provide 15 a simple, efficient, economical device for holding a cloth, sponge, or other mop-like element over and around the discharge orifice of a hose or hose nozzle, the device to be adjustable for different thicknesses or 20 quantities of mop material applied to the hose or nozzle, and to securely hold the same in place on the hose or nozzle irrespective of the even distribution of the mop material about the discharge orifice.

25 In the accompanying drawings which illustrate a selected embodiment of my invention as applied to a hose nozzle—

Figure 1 is a top view of the device in open position.

30 Figure 2 is a side elevation of the same.

Figure 3 is a side elevation showing the device as holding a sponge on the nozzle.

Figure 4 is a side elevation of the device as shown in Figure 3 but looking in a direction at right angles to the view in Figure 3.

35 Figure 5 is a detail view of one of the jaws of the device.

In the particular embodiment of my invention illustrated, the body of the hose nozzle is indicated at 1, the discharge orifices being indicated at 2 and an interiorly threaded fitting 3 is rotatably mounted upon the lower end of the nozzle. Just below or behind the discharge orifices the hose nozzle 40 is provided with a lateral flange 4. The circular base 5 of the nozzle is provided with ears 6 which form hinge butts and between cooperating pairs of these ears are inserted the tongues 7 of arms 8 which are thereby pivoted to the base of the nozzle.

45 The outer or moving end of each arm 8 is provided with a jaw 9 extending transversely of the arm and preferably projecting a substantial distance beyond the same and 50 the side of the nozzle as clearly indicated in Figure 1. The nozzle and arm are so

proportioned that when the arm is swung upwardly into the position shown in Figure 2, the jaw 9 moves toward nozzle 1 and engages the latter at a comparatively short 60 distance below flange 4. The nozzle engaging edge of jaw 9 is recessed as indicated at 10 in Figure 5 so that the jaw partially surrounds the nozzle and it will be understood that this recessing of the jaw permits 65 the projecting portions of the opposing jaws to more closely approach each other than otherwise, thereby permitting the jaws to clamp the sponge between themselves as well as between each other and the nozzle. 70

The lower or outer faces of arms 8 are serrated as indicated at 11 and when elevated are adapted to be engaged by a holding ring 12 which has a circular interior periphery 13 receiving the nozzle base 75 5 and provided with recesses 14 for receiving the arms 8. There is sufficient play between ring 12 and the nozzle for the ring to move transversely of the nozzle, hence the latter does not determine the position of the 80 ring.

With the structure described a sponge A or like material may be placed over the end of the nozzle and clamped between the opposite sides and jaws 9 and it is immaterial 85 whether or not the sponge is evenly distributed on the sides of the nozzle as the pivoted arms are independent of each other and may adjust themselves as required to securely clamp the sponge. For instance, 90 in Figure 3, the righthand arm is shown as being closer to the nozzle than the lefthand arm. In any arm holding position, ring 12 prevents simultaneous movement of the arms away from the axis of the nozzle 95 while permitting their pivotal movement relative to the nozzle. The sponge is securely held against being moved from its position by the force of water discharged through the nozzle not only by the friction 100 of the clamping surfaces of the jaws and nozzle but by the projecting flange 4.

It will be noted that the fitting 3 projects laterally beyond the curved base 5 of the nozzle and prevents ring 12 from dropping from the device. The laterally extending jaws 9 prevent the ring from being slipped off the upper end of the device. Hence there is no opportunity for the holding ring to become disassembled from the 105 arm when the device is not in use.

Obviously, the details of my invention

may be modified without departing from the spirit of my invention as expressed in the appended claims, and I contemplate the exclusive use of such modifications as are suggested in the commercial development of my invention and are included in the scope of the following claims.

I claim:

1. In combination, a nozzle, arms pivoted at the side of said nozzle, transverse jaws on said arms movable toward each other and said nozzle, said jaws being recessed to partially receive said nozzle and more closely approach each other.
2. In combination, a nozzle, a lateral flange spaced from the discharge orifice of said nozzle, arms pivoted at the side of said nozzle so as to swing toward said nozzle, jaws on the swinging portions of said arms extending transversely of said arms for a minimum distance approximating the diameter of said nozzle and so positioned as to

project under said flange when said arms are swung as described.

3. In combination, a nozzle, a lateral flange on the same behind its discharge orifice, and arms pivoted at the sides of said nozzle adapted to swing on their pivots independently of each other to clamp different thicknesses of a cloth, sponge or the like between each arm and said nozzle just behind said flange.

4. In combination, a nozzle, a lateral flange on the same behind its discharge orifice, and an arm pivoted at the side of said nozzle and adapted to swing on its pivot to engage a cloth, sponge or the like between its end and said nozzle just behind said flange and means for clamping said arm in such engaging position.

In testimony whereof I hereunto affix my signature this 21st day of October, 1924.

THOMAS FRANK.
